UNITED STATES PATENT OFFICE.

LOUIS C. ZWERDLING, OF BROOKLYN, NEW YORK, ASSIGNOR OF ONE-THIRD TO HARRY ZWERDLING AND ONE-THIRD TO JOSEPH JOSEPHSON, BOTH OF NEW YORK, N. Y.

FUEL-SAVING CONSTRUCTION FOR FURNACES.

1,132,235.

Specification of Letters Patent. Patented Mar. 16, 1915.

Application filed November 10, 1914. Serial No. 871,241.

To all whom it may concern:

Be it known that I, LOUIS C. ZWERDLING, a citizen of the United States, and residing at Brooklyn, in the county of Kings and State of New York, have invented certain new and useful Improvements in Fuel-Saving Construction for Furnaces, of which the following is a specification, such as will enable those skilled in the art to which it 10 appertains to make and use the same.

This invention relates to steam boilers and furnaces, and the object thereof is to provide improved means for saving fuel and which will also act, to an extent, as a smoke consumer, and with this and other objects in view the invention consists in the application to the escape flue of a furnace or boiler and adjacent thereto of means by which air, preferably heated, is directed into the furnace or the fire tubes of the boiler around the walls of the escape flue, or a part thereof, and by means of which the escape of carbonaceous gases and similar substances through the escape flue is prevented or retarded, and a more perfect combustion secured.

The invention is fully disclosed in the following specification, of which the accompanying drawing forms a part, in which the 30 separate parts of my improvement are designated by suitable reference characters in each of the views, and in which:—

Figure 1 is a sectional view of a steam boiler furnace and showing one form of my 35 improvement in which the escape flue of the boiler or furnace is arranged vertically; Fig. 2 a section on the line 2—2 of Fig. 1; Fig. 3 a section on the line 3—3 of Fig. 1; and, Fig. 4 a view similar to Fig. 1 but 40 showing a modification.

In the drawing forming part of this specification, I have shown at *a* a boiler furnace involving a firebox *a*² and in the top portion of which is placed a boiler *b* having 45 horizontal fire tubes *b*², and in the use of this boiler hot gases of combustion pass backwardly through the firebox then forwardly beneath the boiler and then backwardly through the fire tubes *b*² of the boiler 50 and into and through the escape flue *c* which is provided with a connection *c*² with the boiler which incloses the discharged ends of the fire tubes *b*², and the above given direction of the products of combustion is indi- cated by the arrows *x*. All these features 55 of construction are old and wellknown, and in the practice of my invention as shown in Fig. 1, I provide the escape flue *c* adjacent to its connection *c*² with a cylindrical enlargement *c*³ having inwardly directed and 60 tapered top and bottom ends *c*⁴ and *c*⁵, and within one side of the annular enlargement *c*³ is placed a vertically arranged casing *d*, the lower end of which is preferably inclined 65 downwardly and backwardly as shown at *d*² and perforated, and the upper end of which is open as shown at *d*³, and mounted in the opening *d*³ is a fan wheel *e*. The casing *d* forms a vertical chamber *d*⁴ in 70 one side of the enlarged portion *c*³ of the flue *c*, and placed in the upper end of said chamber, in the construction shown, is a curved buffer plate *d*⁵, and said chamber is also provided below the wheel *e*, in the construction shown, with a transverse partition 75 *d*⁶ having a tubular passage *d*⁷ and below which are baffle plates or devices *d*⁸, *d*⁹ and *d*¹⁰ arranged as shown in Figs. 1, 2 and 4, and the object of which is to retard the 80 passage of air or of air and the products of combustion downwardly through the chamber *d*⁴. The chamber *d*⁴ is also provided on its outer side with an air inlet *d*¹¹ which 85 communicates therewith below the partition plate *d*⁶, and in the operation of this device fresh air enters the chamber *d*⁴ at *d*¹², and the products of combustion passing through 90 the flue *c*, as indicated by the arrows *x*, turn the wheel *e* in the direction of the arrow *x*², and this creates a draft downwardly 90 through the chamber *d*⁴ and the air is discharged from the bottom of said chamber as indicated by the arrows *x*³, and this air is discharged into the hot gases of combustion 95 passing upwardly through the flue *c*, and this air is highly heated and there is also mingled therewith by the wheel *e* a small amount of products of combustion passing upwardly through the flue *c* and the result thereof is to retard the flow of 100 partially consumed gases or carbonaceous substances from the boiler or from the furnace and through the escape flue and to hold the same in the furnace, or in the boiler 105 tubes, until they are more completely consumed, and in this way a saving of fuel is effected, and as will be understood the heavy discharge of black and carbonaceous sub-

stances from the escape flue is modified and reduced to a considerable extent.

The exact form, construction and operation of the baffle devices d^8 , d^9 and d^{10} in the chamber d^4 is immaterial as these devices are only intended to retard the flow of air through said chamber and to heat the same, and any suitable devices of this class may be employed and the partition plate d^6 also 10 serves as a baffle device, and this plate is not essential and may or may not be employed.

In the construction shown in Fig. 4, the flue c is of the same size throughout and the casing d and the chamber d^4 formed thereby are placed on the outer side of said flue, and instead of having perforations in the lower end of the wall d^2 of the casing d , as shown in Fig. 1, perforations f are formed in the flue c at the lower end of the chamber d^4 and a shield g is employed which directs the air currents passing downwardly from the chamber d^4 in a downward direction, as clearly indicated with the arrow x^3 . The other features of construction shown in Fig. 15 4, and involving the air inlet d^{11} , the wheel e and the baffle plates or devices d^8 , d^9 , d^{10} , etc., in the chamber d^4 are the same as in Figs. 1, 2 and 3 and the operation of this 20 form of device will also be similar to that shown in Figs. 1 to 3 inclusive, and herein-before described.

It will be understood, of course, that the casing d or the chamber d^4 may be made of any desired dimensions longitudinally and 35 transversely, and changes in and modifications of the construction herein described may be made, within the scope of the appended claims, without departing from the spirit of my invention or sacrificing its advantages.

I am aware that devices or constructions of the same general character as that described and claimed herein have heretofore been applied to the escape flues of boilers 45 and furnaces, but the distinctive features of my improvement are found in the fact that the fresh air supplied in the manner described is heated before it is discharged into the bottom of the escape flue, or the furnace 50 connection, and in the further fact that there is a forced circulation of the air through the chamber d^4 , the wheel e being automatically operated at all times by the products of combustion passing through the flue c after escaping from the furnace or the tubes of the 55 boiler.

In the accompanying drawing, I have shown my improvement applied to a vertically arranged flue but it will be understood

that the same may be applied to a flue arranged in a horizontal position.

Having fully described my invention, what I claim as new and desire to secure by Letters Patent, is:—

1. The combination with the escape flue 65 of a boiler furnace, of a casing connected with one side portion of said flue adjacent to said furnace and forming an air chamber or passage, the walls of said chamber or passage being provided at the end portion 70 thereof adjacent to the furnace with means for discharging air into the escape flue and adjacent to the opposite end thereof with an air inlet, and said casing being also provided in the end portion thereof opposite 75 the furnace connection with an opening communicating with the escape flue and a fan wheel mounted therein and adapted to be rotated by the products of combustion passing through the flue.

2. The combination with the escape flue 80 of a boiler furnace, of a casing connected with one side portion of said flue adjacent to said furnace and forming an air chamber or 85 passage, the walls of said chamber or passage being provided at the end portion thereof adjacent to the furnace with means for discharging air into the escape flue and adjacent to the opposite end thereof with an air inlet, and said casing being also provided in the end portion thereof opposite 90 the furnace connection with an opening 95 communicating with the escape flue, and a fan wheel mounted therein and adapted to be rotated by the products of combustion passing through the flue, and means for retarding the passage of air through said casing.

3. The combination with the escape flue 100 of a furnace with means for supplying air thereto, comprising a casing connected with one side thereof and into which air is fed at one end and from which air is discharged into the flue at the opposite end, means operated by the products of combustion passing 105 through said flue for forcing air through said casing, and means within said casing for retarding the passage of air therethrough.

In testimony that I claim the foregoing as 110 my invention I have signed my name in presence of the subscribing witnesses this 31st day of October 1914.

LOUIS C. ZWERDLING.
